 Calif., a corporation of California

Application November 18, 1947, Serial No. 786,608

17 Claims. (Cl. 62—129)

1 This invention relates to improvements in reversible cycle refrigeration systems of the type in which the system is shifted from its heating cycle to its cooling cycle by changing the refrigerant circuit, and in which the condensing and evaporating coils or passages used for the heating cycle are distinct from those used for the cooling cycle.

In previous systems of the type described, when the system is to be operated, say, on the heating cycle, valve means must be actuated so that the refrigerant flowing from the compressor to the receiver passes through the appropriate one of the two condensers, and additional valve means must be actuated so that the refrigerant flowing from the receiver back to the compressor passes through the appropriate one of the two evaporators. When the system is to be shifted to the cooling cycle, bringing into action the other condenser and the other evaporator, both valve means must be shifted either simultaneously or by properly coordinated action. Moreover, in such systems check valves are usually required between the condensers and the receiver, to prevent back flow of refrigerant into the condenser which is temporarily idle.

An important object of the present invention is the improvement of such refrigerant-switching systems by generally simplifying the refrigerant circuit, and in particular by reducing the number of switching valves required. This leads to a corresponding simplification of the switching operation itself, since the problem of co-ordinating the various manipulations is minimized or entirely eliminated.

The improved refrigerant circuiting comprises alternative refrigerant circuits each of which includes a condenser and an evaporator. Refrigerant is directed by valve means, for example by a single three-way valve, from the compressor into one or other of the two circuits, and is returned directly from this circuit to the compressor. No additional valving is required, the single valve means being capable of performing the entire switching operation.

The invention has the further advantage of providing more effective use of the charge of refrigerant, since substantially all of the refrigerant in the system is in use both on the heating cycle and on the cooling cycle.

Two separate condensers and two separate evaporators may be provided, one condenser and one evaporator being used on the heating cycle and the other condenser and evaporator on the cooling cycle. Or, for example, the refrigerant

2 coils of the condenser used on one cycle and those of the evaporator used on the other cycle may be fabricated as a single unit, and have common thermal exchange surfaces or fins for thermal contact with a circulated fluid to be heated or cooled. Dual heat exchange units of that type are described fully and claimed in my Patent No. 2,474,304, issued on June 28, 1949. The present invention can be put into effect in a system which uses such dual units, or in a system which does not use them, and in which, for example, four structurally independent heat exchange units are used as the two condensers and the two evaporators.

15 A clear understanding of the present invention, and of its further objects and advantages, will be had from the following description of an illustrative preferred embodiment, which is to be read in connection with the accompanying drawings, of which:

Fig. 1 is a schematic drawing of an illustrative form of reversible refrigeration system embodying the invention;

Fig. 2 is a schematic drawing showing the use of refrigerant subcooling in a system like that of Fig. 1;

Fig. 2a is a fragmentary schematic drawing, corresponding to a portion of Fig. 2, and showing an alternative arrangement; and

30 Fig. 3 is a schematic drawing of a modified reversible refrigeration system, also embodying the invention.

Fig. 1 illustrates use of the invention in a reversible cycle system for heating and cooling air which is circulated from and to the conditioned

35 space through conditioned air duct 10 by fan 11, heat thus exchanged being removed from or rejected to some external medium, here shown as an outside air stream which is circulated through

40 outside air duct 12 by fan 13. Condenser 20 and evaporator 21 are located within conditioned air duct 10 in heat exchanging relation with the air stream therein, and condenser 23 and evaporator 22 are in heat exchanging relation with the

45 stream of outside air within duct 12. The system as illustrated includes also two liquid refrigerant receivers 24 and 25; two expansion valves 26 and 27, which represent any suitable pressure reducing means between the high pressure and the low

50 pressure portions of the respective circuits; switching valve 28; and refrigerant compressor 29, which is driven by any suitable means, such for example as motor 30.

Fluid connections are provided as indicated between the various elements of the refrigerant

system. Line 40 carries compressed refrigerant vapor from compressor 29 to switching valve 28, and is in effect the compressor outlet. Valve 28 is shown schematically as a conventional three-way valve by which line 40 can be connected selectively to one or other of lines 42 and 43. Any suitable means providing such selective connections can be used, such for example as a conventional T-coupling at the position of valve 28 and two separate valves, one in each of the lines 42 and 43 (compare Fig. 3).

From switching valve 28 two refrigerant circuits, a heating circuit and a cooling circuit, lead back to the inlet of compressor 29, these two circuits being distinct from each other throughout their lengths, from the point at which they branch off from compressor outlet 40 to the point at which they join at the compressor inlet, which in effect is line 50. Refrigerant flows through one or other of these circuits, according to the position of switching valve 28.

The heating circuit includes line 42, condenser 20, line 44, receiver 24, line 66, expansion valve 26, evaporator 22 and line 43. The cooling circuit includes line 43, condenser 23, line 45, receiver 25, line 47, expansion valve 27, evaporator 21 and line 49. It will be noted that the only valves which are needed in this system are switching valve 28 and the two expansion valves 26 and 27 which are used alternatively. No check valves are required, although check valves or other additional means for controlling the rate or direction of refrigerant flow may be provided at appropriate points in the system if desired.

When air in duct 18 is to be heated, switching valve 28 is set in the position indicated in Fig. 1, cutting line 40 off from line 43 and connecting it to line 42, so that compressed refrigerant is directed into the above described heating circuit (solid arrows). Compressed refrigerant vapor is then condensed in condenser 20, giving up heat to the outside air stream in duct 12, and is delivered as liquid to receiver 24. Expansion valve 26, which is controlled in any suitable manner, permits flow of refrigerant to evaporator 22 at such a rate as to maintain the system in proper balance. Evaporation of liquid refrigerant in evaporator 22 gives up heat to the outside air stream in duct 12. The resultant refrigerant vapor returns via line 48 to compressor inlet 50 and is recirculated through the system by compressor 29.

When the system is operated thus on its heating cycle, the cooling circuit is cut off from the compressor outlet by switching valve 28 so that no vapor can enter the cooling circuit from compressor 29; but the cooling circuit remains connected via line 49 to the outlet 40 of compressor inlet, so that the pressure within the cooling circuit is maintained at substantially the suction pressure of the compressor. Since all parts of the idle cooling circuit are ordinarily at a higher temperature than, say, the working evaporator 22 of the heating circuit (which is colder than the relatively cold outside air) the vapor pressure of liquid refrigerant in the cooling circuit exceeds the suction pressure in line 48 (which is necessarily less than the vapor pressure in the working evaporator). Therefore, any refrigerant which exists initially within this cooling circuit in the form of liquid, including that within receiver 25, is converted to vapor and is thus substantially wholly removed from the cooling circuit. Expansion valve 27 does not prevent the out-flow of refrigerant under these conditions, although it does limit the rate at which refrigerant

is exhausted from that part of the circuit which includes condenser 23 and receiver 25. This is true, whether the expansion valve is of the pressure regulator type or involves in effect a simple restrictive orifice.

For example, if the expansion valves are so controlled as to open with increasing degree of superheat at the outlets of their respective evaporators, as is the usual practice, it will be seen that the valve in the idle circuit tends to remain open, since the degree of superheat gradually increases as the circuit becomes idle. That is because the pressure remains substantially equal to the compressor suction pressure, and the temperature tends to rise as the evaporator ceases operation and the adjacent condenser (in the other refrigerant circuit) comes into operation and becomes warm. The expansion valve in the idle circuit therefore remains open, or even opens more widely, as the refrigerant liquid in that circuit is removed.

The system is switched to its cooling cycle by the single operation of setting valve 28 to disconnect line 40 from line 42 and connect it to line 43 and the cooling circuit (dashed arrows). Compressed refrigerant vapor is then condensed in condenser 23, giving up heat to the outside air stream in duct 12, and is delivered as a liquid to receiver 25. The liquid then flows through expansion valve 27, and is re-evaporated in evaporator 21, absorbing heat from the conditioned air stream and thus cooling that air. During operation of the cooling cycle, the heating circuit remains connected to the suction side of the compressor at 40, and the refrigerant within the heating circuit is therefore exhausted by the compressor, as has just been described for the cooling circuit during the heating cycle. The idle evaporator 22 of the heating circuit, in the relatively warm outside air stream, is then ordinarily at a temperature higher than that of the active cooling evaporator 21 in the cooled conditioned air stream, so that any liquid in the heating circuit is vaporized and substantially wholly withdrawn.

Thus, whether the system is operated on its heating cycle or on its cooling cycle, the circuit which is not in use is substantially empty of refrigerant, virtually the whole of the refrigerant charge being usefully employed in the active circuit. When the system, after operation for a period on one cycle, is switched to the other cycle, the circuit which was previously active is gradually exhausted through compressor inlet 50; and the circuit which was previously empty is gradually filled with refrigerant through compressor outlet 40 and switching valve 28. In practice only a few minutes are required after switching from one cycle to the other before the transfer of refrigerant between the two circuits is completed and the system attains its new equilibrium.

Since the system is switched from one cycle to the other by operation of the single three-way switching valve 28, the switching operation is greatly simplified as compared with previous systems. Accordingly, there is a corresponding simplification in the control equipment which is necessary to provide automatic switching of the improved system in accordance with varying temperature conditions or the like.

The use of refrigerant subcooling to increase the effective capacity of conventional refrigeration systems is well known. Fig. 2 illustrates a preferred arrangement of subcoolers for use with the improved system shown in Fig. 1. Two dis-

tinct subcoolers 52 and 53 are provided, connected respectively in the heating and cooling refrigerant circuits, preferably between the receiver and expansion valve of the circuit. Thus during the heating cycle liquid refrigerant from receiver 24 in the heating circuit passes via line 46a to subcooler coil 52 and then via line 46b to expansion valve 26. During the cooling cycle liquid refrigerant from receiver 25 reaches subcooling coil 53 via line 47a and is returned to expansion valve 27 via line 47b. During either the heating or cooling cycle, the subcooler which is not in use soon becomes substantially empty of refrigerant, like the remainder of the idle refrigerant circuit.

The advantage to be obtained from a subcooler is greater the lower the temperature of the refrigerant liquid leaving it. It is therefore desirable to place the subcooler coil in as cool a position as possible. It is also desirable, particularly when the condenser is cooled by an air stream (as in the present instance), to avoid placing the subcooler in that air stream in advance of the condenser, since the air reaching the condenser is then warmed in the subcooler, reducing the effectiveness of the condenser. A further consideration in the arrangement of a subcooler in the air circuit is the provision of a satisfactory rate of air flow over the subcooler coils without the need of a special fan or other equipment.

The novel manner of obtaining suitable air streams through the subcoolers, illustrated in Fig. 2, is advantageous in all the respects just mentioned, and greatly increases the utility of the system as a whole, particularly when the refrigerant circuits are also arranged in accordance with the present invention. Subcooler 52 of the heating circuit is placed in the duct 54 through which fresh outside air is drawn by fan 11 into the main conditioned air duct 10. Duct 54 opens into that portion of duct 10 which lies between fan 11 and condenser 20. The air pressure in that portion of duct 10 is appreciably below atmospheric pressure, due to the pressure drop of the air stream passing through the relatively restricted passages of condenser coil 20 (and, in the present instance, of evaporator 21). This low air pressure produces an effective flow of cool outside air through duct 54 and over subcooler 52, and this flow does not interfere with the normal flow of cooling air over condenser 20.

Similarly, subcooler 53 of the cooling circuit is placed in duct 55 which leads from the outside into that portion of outside air duct 12 which lies between fan 13 and condenser 23. Thus on the cooling cycle, a strong blast of outside air is drawn through the air passages of subcooler 53 by the main outside air fan 13. Dampers can be provided if desired in subcooler ducts 54 and 55, for the regulation of air flow therein. However, I prefer to omit such dampers and to allow a uniform amount of fresh air to enter the conditioned space via duct 54 whether that space is being heated or cooled.

It may be desirable to provide a subcooler in only one of the refrigerant circuits, thus increasing the heat exchanging capacity of the system when that circuit is operating. For example, if maximum capacity is required on the heating cycle but not on the cooling cycle, subcooler 53 and the outside air duct 55 in which it is placed may be omitted. The advantages described above will be obtained in connection with the arrangement of subcooler 52 and fresh air duct 54 with relation to fan 11 and condenser 20. In

fact this same type of arrangement is advantageous not only in reversible systems, but is also applicable to ordinary refrigeration systems which use an air stream to cool the condenser, or to reversed cycle systems for heating an air stream.

A modification of the arrangement of Fig. 2, such as that shown in Fig. 2a, retains the advantages just described and has the additional advantage of increasing the capacity of the system when operating on its cooling cycle. In the arrangement of Fig. 2, it is substantially immaterial for the present discussion which of the two blast coils 20 and 21 comes first in the circulated air stream in duct 10, or indeed whether they are incorporated in a unitary structure. In Fig. 2a condenser 20 and evaporator 21 are preferably so arranged that the circulated air passes first through the condenser and then through the evaporator. Makeup air duct 54a opens into duct 10 between the condenser and evaporator, at a position which is downstream from condenser 20 (as is also true in Fig. 2) but upstream from evaporator 21. With this arrangement what has been said in connection with Fig. 2 and with regard to the relationship of duct 54, condenser 20 and fan 11 still applies and the described advantages still obtain. The arrangement of Fig. 2a, however, has the advantage that on the cooling cycle, (when condenser 20 and subcooler 52 are not operating) the relatively warm outdoor makeup air from duct 54a enters the circulated air stream in advance of evaporator 21, increasing the average temperature of the air passing through the evaporator. This permits the evaporator to operate at a higher working temperature, increasing the effective cooling capacity of the system.

Fig. 3 illustrates the use of the present invention in a modified refrigeration system for conditioning a space 59. This system, like that of Fig. 1, includes two separate condensers and two evaporators, but the transfer of heat to or from these units is carried out in a different manner. The system of Fig. 3 is intended to be illustrative of some of the many different types and combinations of heat exchanging devices which can be used with my invention. Compressed refrigerant vapor leaves compressor 29 via outlet line 40a to the T-connection 56, from which two distinct refrigerant circuits, for heating and cooling respectively, lead back to compressor inlet line 50a. The heating circuit leads from T-connection 56 through control valve 57 to condenser 20a, receiver 24a, expansion valve 26a and evaporator 22a. The cooling circuit leads from T-connection 56 through control valve 58, condenser 23a, receiver 25a, expansion valve 27a and evaporator 21a. In this system, the heating cycle is put into operation by opening control valve 57 and closing valve 58, and the cooling cycle by closing valve 57 and opening valve 58. No other control valves are required. Condenser 20a, by which the conditioned space 59 is heated, is not directly exposed to an air stream which enters this space, but gives up its heat to an auxiliary fluid, such as water, which is circulated by pump 60 through tank 61 enclosing condenser 20a and through radiator 62 which is located within conditioned space 59. On the other hand, evaporator 21a, by which the conditioned space is cooled, is shown located within a duct 65 and exposed to a stream of air which is recirculated from the conditioned space by fan 66.

Evaporator 22a in the heating circuit and condenser 23a in the cooling circuit, which do not

operate simultaneously, are in heat exchanging relation with a stream of water from any convenient source (not shown) which circulates in series over the coils of the two heat exchanging units in tanks 67 and 68 respectively, entering via line 70 and leaving via line 71. This water stream thus performs a similar function to that of the outside air stream in the system of Fig. 1. Alternatively, evaporator 22a might receive heat from any other suitable heat source, and condenser 23a might give up heat to any suitable medium.

The particular means for transferring heat to and from the various heat exchange units in the systems shown in Figs. 1 and 3 are illustrative of possible arrangements, but neither these nor other details of the above described embodiments of the invention are intended as limitations upon its scope.

I claim:

1. In a reversible refrigeration system, two independent refrigerant circuits, each having a relatively high pressure portion including a refrigerant condenser, a relatively low pressure portion including a refrigerant evaporator, and each having a fluid connection between the two said portions including means adapted to limit the rate of refrigerant flow from the high pressure portion to the low pressure portion, and means including a refrigerant compressor for transferring refrigerant vapor from the low pressure portions of both refrigerant circuits selectively to the high pressure portion of either of the circuits, those portions of the two circuits lying between the respective condensers and evaporators being mutually distinct.

2. A reversible refrigeration system as defined in claim 1 and in which both said refrigerant circuits are continuously open for refrigerant flow from their respective high pressure portions via their low pressure portions to the said refrigerant compressor.

3. A reversible refrigeration system as defined in claim 1 and in which both said refrigerant circuits are continuously open for refrigerant flow in either direction between their respective high pressure and low pressure portions.

4. A reversible refrigeration system adapted for selectively heating or cooling a space, and comprising refrigerant vapor compressing means having a refrigerant inlet and a refrigerant outlet, two refrigerant circuits leading from said outlet to said inlet, each of said circuits including refrigerant condensing means, pressure reducing means and refrigerant evaporating means, means for transferring heat from the condensing means of one circuit to the said space and from the said space to the evaporating means of the other circuit, means for supplying heat to the evaporating means of the said one circuit and for removing heat from the condensing means of the other circuit, and means for limiting the flow of refrigerant from the compressor outlet selectively to either of the said circuits, the refrigerant passages of the two said refrigerant circuits being mutually independent.

5. A reversible refrigeration system for selectively heating or cooling a fluid, said system comprising refrigerant vapor compressing means having a refrigerant inlet and a refrigerant outlet, two parallel circuits for refrigerant flow from the said outlet to the said inlet, each of said circuits including refrigerant condensing means, pressure reducing means and refrigerant evaporating means, means for bringing the said fluid into

heat exchanging relation with the condensing means of one circuit and with the evaporating means of the other circuit, means for bringing at least another fluid into heat exchanging relation with the evaporating means of the said one circuit and with the condensing means of the other circuit, and valve means between the compressing means and the two condensing means and adapted to direct the flow of refrigerant from the compressing means selectively into either of the two circuits, the refrigerant passages of the two said parallel circuits being mutually distinct.

6. A reversible refrigeration system as defined in claim 5 and in which both said circuits are open for refrigerant flow from their respective condensing means to the said compressor inlet, subject only to the said pressure reducing means of each circuit, and regardless of the condition of the said valve means.

7. A reversible refrigeration system as defined in claim 5 and in which both said circuits are open for refrigerant flow in either direction between their respective condensing means and their respective evaporating means, subject only to the said pressure reducing means of each circuit, and regardless of the condition of the said valve means.

8. A reversible refrigeration system for selectively heating or cooling a fluid, said system comprising refrigerant vapor compressing means having a refrigerant inlet and a refrigerant outlet, two parallel circuits for refrigerant flow from the said outlet to the said inlet, each of said circuits including refrigerant condensing means, pressure reducing means and refrigerant evaporating means, means for bringing the said fluid into heat exchanging relation with the condensing means of one circuit and with the evaporating means of the other circuit, means for supplying heat to the evaporating means of the said one circuit and for removing heat from the condensing means of the other circuit, and valve means between the compressing means and the two condensing means and adapted to direct the flow of refrigerant from the compressor selectively into one of the two circuits, the refrigerant passages of the two said parallel circuits being mutually distinct.

9. A reversible refrigeration system as defined in claim 8 and in which each of the said circuits includes also a receiver for liquid refrigerant, located between the condensing means and the pressure reducing means.

10. In a reversible refrigeration system which is adapted for transferring heat in either direction between a first and a second fluid and which comprises first and second refrigerant condensing means, first and second refrigerant evaporating means, means for flowing the first said fluid in heat exchanging relation with the two said first means, refrigerant vapor compressing means, each of the said means having a refrigerant inlet and a refrigerant outlet, means for flowing the second fluid in heat exchanging relation with the two said second means, fluid connections from the outlets of the two evaporating means to the inlet of the compressing means, fluid connections from the outlet of the compressing means to the inlets of the two condensing means, and valve means in the last mentioned fluid connections adapted to direct refrigerant from the compressor selectively to one or other of the two condensing means; the improvement which comprises one fluid connection between the outlet of the first condensing means and the inlet of the second evaporating

means, and a second fluid connection between the outlet of the second condensing means and the inlet of the first evaporating means, the two last mentioned fluid connections being independent of each other.

11. A reversible refrigeration system as defined in claim 10 and in which both of the two last mentioned fluid connections are open for refrigerant flow independently of the condition of the said valve means.

12. A reversible refrigeration system as defined in claim 10 and in which each of the two last mentioned fluid connections includes a receiver and a pressure reducing means.

13. A reversible refrigeration system as defined in claim 12 and in which at least one of the two last mentioned fluid connections includes heat exchange means interposed between the receiver and the pressure reducing means and adapted to remove heat from refrigerant fluid passing therethrough.

14. In a reverse cycle refrigeration system which is adapted for heating a space and which includes an air passage communicating at both ends with the space, a fan in the air passage adapted to circulate air through the passage from the space, refrigerant vapor compressing means having an inlet and an outlet, a refrigerant circuit leading from the outlet to the inlet and including refrigerant condensing means arranged in the air passage ahead of the fan, refrigerant pressure reducing means and refrigerant evaporating means, and means for removing heat from the refrigerant evaporating means; the improvement which comprises a second air passage communicating between the outside air and that portion of the first said air passage which lies between the condensing means and the fan, a refrigerant passage in heat exchanging relation with air in the second air passage, and means for conducting refrigerant from the condensing means through the refrigerant passage to the pressure reducing means.

15. In a reversible refrigeration system which is adapted for selectively heating or cooling a space and which comprises a first air passage communicating at both ends with the space, a fan in the said passage adapted to circulate air from and to the space through the said passage, a refrigerant condenser and a refrigerant evaporator arranged in the said passage, at least the condenser being located ahead of the fan in the passage air stream, means adapted to circulate fluid refrigerant selectively as vapor to the condenser and as liquid to the evaporator; the improvement which comprises a second air passage communicating between the outside air and the first said air passage, a refrigerant coil arranged in the second air passage and adapted to receive refrigerant liquid condensed in the condenser, the second air passage communi-

cating with the first passage at a point which lies between the condenser and the fan.

16. A reversible cycle refrigeration system as described in claim 15 and in which the evaporator is located in the first air passage between the fan and the point of communication between the two air passages.

17. In a reversible refrigeration system which is adapted for selectively heating or cooling a space and which comprises a first passage communicating at both ends with the space, a fan in the said passage adapted to circulate air from the space through the said passage, a second passage communicating at both ends with the outside air, a fan in the second passage adapted to circulate outside air through the second passage, a first refrigerant condenser and a first refrigerant evaporator arranged in the first air passage, at least the condenser being located ahead of the fan in the air stream, a second refrigerant condenser and a second refrigerant evaporator arranged in the second passage, at least the condenser being located ahead of the fan in the air stream, first and second refrigerant pressure reducing means, and means, including a refrigerant compressor, for circulating refrigerant selectively through a first refrigerant circuit which includes successively the first condenser, the first pressure reducing means and the second evaporator, or through a second refrigerant circuit which includes successively the second condenser, the second pressure reducing means and the first evaporator; the improvement which comprises a third passage communicating between the outside air and that portion of the first passage which lies between the fan and the said first condenser, a fourth passage communicating between the outside air and that portion of the second passage which lies between the fan and the said second condenser, a refrigerant coil connected in the first said refrigerant circuit between the condenser and the pressure reducing means and arranged in heat exchanging relation with air in the third said passage, and a refrigerant coil connected in the second said refrigerant circuit between the condenser and the pressure reducing means and arranged in heat exchanging relation with air in the fourth said passage.
